METHOD OF MAKING BOTTLES

Roy J. Held, Freeport, Ill.

Application January 6, 1936, Serial No. 57,680

2 Claims. (Cl. 29—148.2)

The invention relates to bottles and more particularly to a method of making an all metal bottle.

The object of the invention is to provide a simple and efficient method of making a metal bottle from a one piece metal blank and a metal sleeve. More particularly, according to the present invention, the body portion of the bottle is formed from a unitary piece of metal by extruding or drawing and spinning operations, and the metal sleeve having a tapping tool receiving part and preferably also a cap anchoring means is secured to said body in a fluid tight manner, preferably by a welding operation.

15 The invention further consists in the method and steps of the method hereinafter set forth and more particularly defined by claims at the conclusion hereof.

In the drawing:

20 Fig. 1 is a vertical sectional view of a metal blank shown in plan in Fig. 2 which may be used in carrying out the method;

Fig. 3 is a vertical sectional view of the blank after an extruding, drawing, or spinning operation thereon;

Fig. 4 is a detail sectional view of one form of cap-receiving sleeve;

Fig. 5 is a vertical sectional view after spinning operations on the structure shown in Fig. 3;

30 Fig. 6 is a detail sectional view of the neck portion of the finished bottle.

A blank 7 of circular or other suitable form such as a ball or slug and of aluminum alloy, stainless steel or other suitable metal or suitably surfaced metal is subjected to an extruding, drawing, or spinning operation to form a closed end tube 8 whose bottom wall 9 may be relatively thicker than the sides of said tube and preferably is inwardly concave, as shown in Fig. 3 or otherwise strengthened from the original metal.

40 This closed end tube is then subjected at its upper end to a spinning operation to form the contracted breast wall 10 and the neck 11 of the

bottle shown in Fig. 5, it being noted that the wall 10 is thicker than the side wall 12 but not always as thick or otherwise reinforced as the bottom wall 9.

A metal sleeve member 13 is formed to reinforce the neck and provide a cap-receiving bead 14 and a tapping or filling tool receiving flange or recessed portion 15, its inside diameter being such as to closely fit the neck 11 of the bottle to which it is applied as shown in Fig. 6 and then secured thereto in fluid tight manner preferably by a welded seam 16 between the top of the mouth and the inner wall of the bead and a welded seam 17 joining the lower end of said tube with the outer wall of the bottle. This sleeve member is preferably the same kind of metal as the bottle body and non-corrodible by any potable beverage including beer or ale with which the bottle may be filled, so that it will not affect such beverage or be affected by it.

I desire it to be understood that this invention is not to be limited to the particular details hereinbefore set forth except in so far as such limitations may appear in the claims.

What I claim as my invention is:

1. The method of forming a metal bottle which comprises forming a closed end tube from a unitary piece of metal by drawing the metal from a blank over a suitable die, spinning the upper end of said tube to form a contracted breast and a tubular neck, and welding one end of a tubular metal bottle cap-receiving member in fluid tight engagement with said neck at the end of said neck and the other end of said member to the outer end of said neck.

2. The method of forming a metal bottle which comprises forming a closed end tube from a unitary piece of metal by suitable drawing operations, spinning the upper end of said tube to form a contracted breast and a tubular neck, placing a tubular metal bottle cap-receiving member over said neck and welding said member to said neck at the end of said neck.

ROY J. HELD.
